Charles Howard Inventor
By his Attorney A. M. Pierce.

UNITED STATES PATENT OFFICE.

CHARLES HOWARD, OF NEW YORK, N. Y.

DESIGN FOR A GRATE.

SPECIFICATION forming part of Design No. 26,495, dated January 5, 1897.

Application filed November 30, 1896. Serial No. 614,008. Term of patent 14 years.

To all whom it may concern:

Be it known that I, CHARLES HOWARD, a citizen of the United States, residing in the city, county, and State of New York, have invented and produced a new and original Design for Furnace-Grates, of which the following is a specification.

In the accompanying drawings, Figure 1 is a plan view of my design for furnace-grates. Fig. 2 is a side elevation, and Fig. 3 is a cross-section at line *a a* of Fig. 1.

Like numerals of reference, wherever they occur, indicate corresponding parts in all the figures.

Reference being had to the drawings, 1 is

the grate-frame, having a central depression 2, square depression 6, and cross-bars 3.

4 are the bars of the grate, provided with side lugs 5 and square depressions 6.

The leading features of my design consist 20 in the frame 1, provided with depressions 6 and cross-bars 3, whereon are the bars 4, provided with depressions 6 and lugs 5.

What I claim is—

The design for a furnace-grate, substantially as shown and described.

CHARLES HOWARD.
